UNITED STATES PATENT OFFICE.

GEORGE PENMAN GRAHAM, OF SOUTH CHICAGO, ILLINOIS.

CAST-METAL CROSSING.

SPECIFICATION forming part of Letters Patent No. 391,961, dated October 30, 1888.

Application filed May 15, 1888. Serial No. 273,935. (No model.)

To all whom it may concern:

Be it known that I, GEORGE PENMAN GRAHAM, of South Chicago, in the county of Cook and State of Illinois, have invented certain new and useful Improvements in Cast-Metal Crossings; and I do hereby declare that the following is a full, clear, and exact description thereof, reference being had to the accompanying drawings, and to the letters of reference to marked thereon, which form a part of this specification.

This invention relates to cast-metal railway-crossings, or means employed at the intersection of railway-tracks for securing together the track-rails.

The invention consists in the novel details of construction herein shown, described, and more particularly pointed out in the claims.

In the accompanying drawings, illustrating my invention, Figure 1 is a plan view of my novel railroad-crossing, illustrating the several rails in position. Fig. 2 is a vertical sectional view of the same, taken upon line 2 2 of Fig. 1, looking in the direction shown by the arrows.

In said drawings, A is a flat plate or sole-plate of cast metal, preferably steel, having the usual projections or arms, A', and adapted to be placed under the meeting ends of four track-rails at the point where the latter intersect each other. Said arms A' are shown in the drawings as arranged at right angles with each other, but in cases where the rails cross obliquely the arms will of course be correspondingly inclined. Cast integral with the arms A' of said sole-plate and extending upward to the full height of rails placed upon the sole-plate are vertical flanges or (as they are sometimes called) "wing-rails" B B.

C C are horizontal extensions or fillings cast integral with the flanges B B and having their lower surfaces separate from and above the adjacent upper surface of the sole-plate A, so as to leave grooves or openings c c, extending inwardly beneath said fillings, as clearly shown in the sectional view, Fig. 2.

D D' are the adjacent ends of two rails arranged in alignment with each other, and D' D'' are adjacent ends of two other rails arranged in alignment with each other at right angles to the rails D D'. The ends of said rails D D' D'' rest upon the arms A' A' of the sole-plate A, with the flanges of the rails

within the grooves c c and the webs d d of the rails in contact with the fillings C C. In the particular construction illustrated the ends of 55 the rails D and D' are separated a sufficient space to give passage to the wheel-flanges, while the rail D', which is at right angles with and adjacent to the rail D', abuts against the end of the latter, the end of the rail D' being 60 separated from the adjacent side margin of the rail D' in the manner illustrated.

The several flanges B B, in connection with the rails arranged as above described, form continuous horizontal grooves for the wheel-flanges, which grooves cross each other at the middle of the sole-plate in the manner shown 65 in the drawings. The fillings C C of course form the bottoms of said grooves, the fillings being made continuous or integral at the intersection of the said flanged grooves in a manner readily understood.

The outer surfaces of the several flanges B B are preferably vertical and flat, except at their lower portions, at which points they are provided with small fillets b b. The faces or margins C of the fillings C C which come in contact with the webs of the rails are rounded at their upper and lower corners to closely fit against the said webs between the tread and 70 flange of the rail in the manner clearly shown in Fig. 2.

The rails are secured to the casting, made as above described, by means of horizontal bolts E E, passing through the webs of the rails and 75 through openings b' in the said wing-rail B.

In operation the cast sole-plate A is first placed in position at a railroad-crossing and bolted or spiked securely to the ties, it being of course understood that four of said 80 plates are commonly used for one crossing. The tread-rails D D' D'' are then severally secured in place and bolted to the flanges B B, as above described. It will be observed that the flange or wing-rail B acts as a guard for the 85 flanges of the wheels, but at the same time receives no bearing therefrom nor any jars from the wheels, and their entire load is borne directly by the tread rails D and the flat horizontal portion of the sole plate A, which rests, 90 as above mentioned, upon the ties or sleepers. It will thus be seen that when the rails become worn, as they very quickly do at this particular place upon a railroad-bed, they may be 95 100

easily removed by removing the bolts E E and a new rail placed in position.

I am aware that steel or other cast metal has been used heretofore in the construction of railroad-crossings; but I do not believe and do not know that a cast-steel crossing with a guard-rail and filling cast integral therewith have ever been used for this purpose. I have shown the extensions A' of the sole-plate A at right angles with each other; but it is obvious that these extensions may be placed at any angle to form switches or "Y's" in a road-bed, as is well understood by all railroad men.

I claim as my invention—
15 1. The cast-metal railway-crossing consisting of a flat sole-plate provided with four angularly-disposed vertical flanges or guard-rails cast integral therewith, said guard-rails having lateral extensions or fillings extending partially over said sole-plate, said flanges and extensions being provided with substantially horizontal bolt-holes, substantially as described.
20 2. A cast-metal railway-crossing consisting

of a flat sole-plate provided with four angularly-disposed vertical flanges or guard rails cast integral therewith, said guard-rails having lateral extensions or fillings sufficiently below the top edge of the guard-rail to clear the wheel-flange, and said fillings being cast continuous at the center of the crossing, substantially as described.

3. The combination, with a cast-metal railway-crossing consisting of a flat sole-plate and four angularly-disposed vertical flanges or guard-rails cast integral therewith, said guard-rails being provided with lateral extensions, of tread-rails resting upon said sole-plate and bolted to the guard-rails, substantially as described.

In testimony that I claim the foregoing as my invention I affix my signature in presence of two witnesses.

— GEORGE PENMAN GRAHAM.
